UNITED STATES PATENT OFFICE.

GEORGE GORDON BOWER, OF BAINBRIDGE, GEORGIA.

PROPELLER.

1,023,501.

Specification of Letters Patent. Patented Apr. 16, 1912.

Application filed September 11, 1911. Serial No. 648,809.

To all whom it may concern:

Be it known that I, GEORGE G. BOWER, a citizen of the United States, residing at Bainbridge, in the county of Decatur and 5 State of Georgia, have invented a new and useful Propeller, of which the following is a specification.

The present invention relates to improvements in propellers, that is a novel form and 10 an arrangement of propelling mechanism for boats, air-ships and aeroplanes, and the primary object of the invention, is the provision of a rotating casing, disposed vertically, and having adjustably disposed there- 15 within an eccentrically disposed circular cam, co-operatively disposed with relation to a plurality of paddles or blades, whereby on rotation of the casing, the cam being stationary, the paddles or blades, are successively projected beyond the periphery into 20 propulsion position and retracted within the casing when out of such position thus presenting at the proper time the maximum blade resistance, and at other times retracting the blade or blades to reduce the friction. 25

By means of the adjustability of the cam for projecting and retracting the blades or paddles relatively to the casing, it is possible 30 to impart a perpendicular movement to an airship or aeroplane and thus render it unnecessary to get a gliding or inclined start, as is the present practice, while when applied to a boat, the casing and its blades 35 or paddles being completely submerged and disposed in pairs upon opposite sides of the boat throughout the length thereof, it is possible to reverse the propulsive action of the blades or paddles, without reversing the 40 motion of the casing, motor or engine, or even reducing the speed of the motor or engine; to act upon the water in a horizontal plane from above or below to raise either end of the boat or the entire boat in passing 45 over bars or shoals or to elevate the bow or stern when desired; and further to cause all the propellers upon one side to impart to that side a downward list, while those upon the other side impart an upward list, as for 50 instance in firing heavy ordnance for great distances or range. Further by reason of the independent manipulation of the propellers, those upon one side may be rotated to act upon the water in a reverse direction, 55 while those upon the other side act upon the water in a forward direction, thus making

it possible to turn the boat in a very short distance, and also provide in case a rudder should be lost or become useless a means for propelling and simultaneously steering the 60 boat.

With the foregoing and other objects in view which will appear as the description proceeds, the invention resides in the combination and arrangement of parts and the 65 details of construction hereinafter described and claimed, it being understood that changes in the precise embodiment of the invention herein disclosed within the scope of what is claimed may be made without 70 departing from the spirit of the invention.

In the drawings:—Figure 1 is a side elevation of a vessel with the present invention shown applied thereto. Fig. 2 is a section taken on line 2—2 of Fig. 1, looking 75 downwardly. Fig. 3 is a cross section through the vessel in line with a single pair of the propellers. Fig. 4 is an elevation of a propeller with one side of the casing removed, the various positions of the paddles or blades being illustrated in dotted, dot-and-dash, and dash lines. Fig. 5 is a vertical central section through the propeller as viewed in Fig. 4, the full propeller casing being shown. Figs. 6 and 7 are views of a 80 modified form employing two pairs of blades. Fig. 8 is an elevation of a modified form employing an auxiliary hood to provide for use of large blades. Fig. 9 is a side elevation of a vessel equipped with a 85 motor actuated reversing mechanism. Fig. 10 is a view similar to Fig. 6 of another 90 modified form of propeller.

Referring to the drawings, the numeral 1 designates a boat, having disposed in pairs 95 upon opposite sides thereof, as clearly illustrated in Figs. 1 and 2, the vertically disposed propellers 2. These propellers are operated from a common source of power (not shown), which may be steam, or explosive engines, and are applied to any form of vessel without the usual wells that are used when employing many proposed forms of propellers.

In practice, a sleeve 3, is projected 105 through the hull of the boat, and is provided with a stuffing box 4, this sleeve being capable of being manually rotated by means of the lever and ratchet 5, or the pneumatic control C, as shown in Fig. 9. Incased within this sleeve and projecting beyond both ends thereof is the propeller shaft 6,

whose inner end is provided with power transmitting means 7, for operable connection with the source of power, said shaft being the rotatable member and being constantly rotated when the boat is to be in motion. Upon the outer end of the shaft is attached and rotatable therewith a circular disk 8, which is concaved to form with a similarly shaped but oppositely disposed disk 9, a propeller casing 10, the disk 9, being rotatably mounted upon the sleeve 3, beyond the inner face of the circular cam 11, which is keyed upon the shaft 6, eccentrically thereof and within and to the casing 10. By means of the lever and ratchet 5, or pneumatic control C, the sleeve 3 is moved to change the relative position of the cam 11, as indicated in dotted lines Fig. 4. Disposed within the casing 10 are the two parallel plates 12 which at all times rest upon the peripheral edge of the cam 11, as shown in Fig. 4, the tie-rods 13, connecting said plates and holding them in such relative position, said tie-rods spanning or straddling the cam and shaft, as clearly shown. Carried rigidly by and projecting centrally from the respective plates 12, are the propeller blades or paddles 14, each one of which is projected and retracted radially of the casing 10 by means of the cam and plates 12, during the rotation of the casing about said cam, blades when propelling the vessel forwardly acting as shown in full lines Fig. 4, the casing 10 being rotated at all times in the direction of the arrow. Should it be desired to reverse the motion of the boat, the cam 11 is rotated by its sleeve 3 to assume the position in dotted lines, or exactly diametrically opposed to the reverse direction, thus causing the blades to be projected when at the top of the casing 10, and as the casing is completely submerged and is rotated in the direction of the arrow, the blades impart to the boat a direction opposite to the full line position.

Should it be desired to list the boat or raise the same, the cam is moved to the position as shown in dash lines Fig. 4, at which time the blades will act at right-angles to the other described positions and downwardly upon the body of water, thus imparting a lift-effect to the boat at that point. While should it be slightly submerged, that is depress the stern to lift the bow, and vice versa, the cam is operated to assume the position as shown in dot-and-dash lines Fig. 4, at which time the paddles or blades will act upwardly upon the body of water and exert a pressure to pull downwardly that portion of the boat.

Where a series of these propellers are employed as shown in Figs. 1 and 2, it will be seen that all upon one side may assume the position as shown in full lines Fig. 4, while those upon the other side may assume the

position as shown in dotted lines, Fig. 1, thus imparting a spinning motion to the boat so that the boat may be turned within its length, or nearly so. If all upon one side of the boat are caused to assume the dash position, while those upon the other side assume the dot-and-dash position, it is apparent that one side will be lifted and the other lowered, thus imparting a list to the boat, this angle of which may be regulated by the relative positions of the cams between the perpendicular and 90 degree position as shown in Fig. 4, the greatest list being at the direct 90 degree position, while the graduated list will be imparted therebetween in either direction.

In the form of propeller shown in Figs. 6 and 7, the cam 15, is provided with a central circumferential rib or ridge 16, whereby two sets of plates 17, and blades 18, disposed at right angles relatively to each other is used, thus providing four blades, instead of two, as in the other views, the casing 19, being provided with four apertures 20 and guide slots 21, instead of two. In this case the casing rotates similarly to the other structures, the cam being stationary, so that the blades are projected and retracted exteriorly of and within the casing, as in the other case.

Where it is desirable to employ longer blades that project when retracted slightly beyond the periphery of the casing, as shown in Fig. 8, a segmental hood or cap 23 is placed exteriorly of the casing 24, and provides a means for housing the projecting ends 22 of the blades, said hood being attached to the sleeve 3' and operable with the cam 24', said casing being provided with a groove 25, to permit the excess water to flow and not effect the retardation of the propeller.

In the control C, as shown in Fig. 9, said control being employed for large vessels where the manual manipulation would be impractical, a pneumatic cylinder 26, with a piston 27, is operably connected to the bar 28, which operably connects the cam sleeves 3 together for operation in unison, the device 29, being employed to permit the operation of certain ones, or all upon one side in unison, as desired.

In the form of propeller shown in Fig. 10 the cam 15' is straddled by the short ends of the respective frames 33 and 34 thus dispensing with the guiding and projecting ends as viewed in Figs. 4 and 6. The blades 18' and casing 19' are made and disposed as in the other cases.

From the foregoing description taken in connection with the drawings, it is evident that a positive forward and reverse movement and perpendicular impulse or stroke against the water is possible, avoiding any slipping action or the forming of a cavity

due to centrifugal force and the engaging of the water at all points of the circumference of the propeller; that the present form of propeller may be used advantageously with 5 one way rotation turbines as the cam device reverses the propelling action of the propeller without changing the direction of rotation of the propeller; that the same may be actuated to steer, spin and list a boat, 10 and to impart perpendicular movement to an aeroplane or airship, this all being accomplished without effecting the slackening of the propeller or without feathering or turning the blades.

15 What is claimed, is:—

1. A propeller, having a casing composed of two concaved disks the peripheral portion of which provides a tapered in cross section water cutting surface, said casing being provided with a plurality of equi-distantly disposed radial slots through the periphery thereof, a shaft disposed concentrically of the casing and connected to the outer disk, a sleeve rotatably mounted upon 20 said shaft and forming a bearing for the other disk of the casing, a cam keyed to and disposed eccentrically upon the sleeve within the casing, the casing and shaft being disposed to rotate in one direction at all times, 25 and when in operable relation to be completely submerged, a plurality of frames disposed to ride upon the cam and within the casing, a blade to each slot of the casing connected to and carried by said frames to be retracted and projected through the respective slots of the casing due to the rotation of the casing.

30 2. A propeller, having a casing composed

of two concaved disks, the peripheral portion of which provides a tapered in cross 40 section water cutting surface, said casing being provided with a plurality of equi-distantly disposed radial slots through the periphery thereof, a shaft disposed concentrically of the casing and connected to the 45 outer disk, a sleeve rotatably mounted upon said shaft and forming a bearing for the other disk of the casing, a cam keyed to and disposed eccentrically upon the sleeve within the casing, the casing and shaft being disposed to rotate in one direction at all times, 50 and when in operable relation to be completely submerged, a plurality of frames disposed to ride upon the cam and within the casing, a blade to each slot of the casing 55 connected to and carried by said frames to be retracted and projected through the respective slots of the casing due to the rotation of the casing, the length of the said blades being greater than the width of the 60 casing so that a portion thereof normally projects beyond the periphery of the casing when in retracted position, and a guard hood connected to and rotatable with the sleeve, 65 said hood being disposed in an opposite position to the cam and fitting upon and about the portion of the casing to inclose the ends of the retracted blades.

In testimony that I claim the foregoing as my own, I have hereto affixed my signature 70 in the presence of two witnesses.

GEORGE GORDON BOWER.
